UNITED STATES PATENT OFFICE

CHARLES R. KEERAN, OF EVANSTON, ILLINOIS, ASSIGNOR TO DUR-O-LITE PENCIL COMPANY, OF CHICAGO, ILLINOIS, A CORPORATION OF ILLINOIS

MECHANICAL PENCIL

Application filed September 4, 1928, Serial No. 303,647. Renewed March 15, 1930.

This invention relates to an improvement in a mechanical pencil and its purpose is to provide a simple lead-propelling mechanism, including the usual screw-threaded plunger, but so designed that if the lead becomes jammed, or when the screw reaches the end of its operative movement, the forced rotation of the parts will not cause injury or breakage. The invention consists in certain features and elements of construction in combination as herein shown and described and as indicated by the claims.

In the drawings:

Figure 1 is an enlarged axial section of a mechanical pencil embodying this invention.

Figure 2 is a side elevation of a liner tube for the barrel.

Figure 3 is a transverse section taken as indicated at line 3-3 on Figure 1.

Figure 4 is a transverse section taken as indicated at line 4-4 on Figure 1.

Figure 5 is a fragmentary axial section of certain parts of the feed mechanism on an enlarged scale.

Figure 6 is a view similar to Figure 5 showing a modified structure.

Figure 7 is a transverse section taken as indicated at line 7-7 on Figure 6.

In general the pencil illustrated in Figure 1 is of a familiar type, having a barrel, 1, which may be understood as being molded of bakelite or similar material, and a tapered metallic tip, 2, rotatively engaged with the reduced end portion of the barrel, 1. The lead, 3, is fed through the terminal, 4, of the tip, 2, by means of a plunger, 5, having a threaded portion, 6, engaged with the threads in the contracted neck portion, 7, of a cylindrical extension, 8, carried by the tip 2, and projecting into the bore of the hollow barrel, 1. Said bore is fitted with a metallic tubular lining, 9, which may be secured therein during the process of molding the barrel, 1, and which provides a bearing for the extension, 8, in rotation of the tip, 2.

It will be understood that the bore of the barrel with its lining tube, 9, provides a non-circular feature in the nature of a longitudinal channel, while the upper or innermost end 50 of the threaded portion, 6, of the plunger is

formed with a co-operating feature to prevent rotation of the plunger within the barrel. This insures that when the tip, 2, is rotated on the barrel, the threads at 7 will cause the plunger to be fed longitudinally for propelling the lead. 55

The tip, 2, is further provided with a guide tube, 10, and a split sleeve, 11, of resilient metal adapted to frictionally grip the lead, 3, in the vicinity of the terminal, 4. The sleeve, 11, is of such a length that when the plunger, 5, enters the opposite threaded end of said sleeve far enough to begin feeding the lead out of the terminal, 4, the threaded portion, 6, of the plunger will also enter this threaded end of the split sleeve, 11, separating it slightly for this purpose and thus causing it to become frictionally engaged on the threads. This arrangement permits the feed mechanism to "repel" or in other words 60 retract the lead within the tip by reversed rotation of the latter, because the split sleeve, 11, acts as a coupling by virtue of its frictional grip upon the lead at one end and upon the threads at the other, and draws the lead back 65 into the tip.

In a pencil of this type when the bore of a barrel is provided merely with a groove or key-way, and the upper end of the plunger is flattened or formed with a laterally extending key which is positively engaged in such key-way, it will be seen that as the key reaches the threaded neck, 7, it will block further rotation of the tip. If, at such a time, the user does not realize that the last of the lead has been expelled, he may attempt to force further rotation of the tip, 2, and may thus twist off the end of the threaded plunger, 6, or otherwise damage the mechanism. The same thing may happen if the leads should become jammed in the bore of the terminal, 4, so as to oppose longitudinal movement of the plunger; the key-way in the bore of the barrel being positively engaged with the plunger will simply result in stripping of the threads on the plunger or in the neck, 7, if forced rotation is continued at the tip. 80

The present invention protects the mechanism against such injury by providing the 85

upper end of the threaded portion, 6, of the plunger with means which yieldingly holds the plunger against rotation in the barrel, but will permit it to turn when the longitudinal movement of the plunger is definitely opposed either because it has reached the end of its normal travel or because its travel is obstructed as by jamming of the lead in the tip. As shown in Figure 1, the liner tube, 9, is cylindrical at the outer or lower end portion which serves as a bearing for the part, 8, of the tip, but the remainder of the length of the tube is polygonal in cross section,—preferably hexagonal,—so that its flat sides 10 form longitudinal channels of V-shaped cross section extending along the bore of the barrel. The upper end of the threaded plunger, 6, is rigidly secured in the head of a small metallic shell, 12, of approximately cylindrical form having slits, 13, cut in its cylindrical wall to render it somewhat resilient. In the portions of the wall between said slits the shell has small outwardly projecting convex nodes or bumps, 14, which are disposed at 15 intervals to register in the V-shaped channels formed by the hexagonal tube, 9. These nodes or bumps, 14, thus ordinarily prevent rotation of the shell, 12, and of the threaded plunger, 6, in the bore of the barrel, while 20 they do not oppose longitudinal movement of the shell, but serve merely as keys in these channels or guideways in the normal feeding action. However, if the longitudinal advance of the threaded plunger is opposed, as 25 for example, when the threaded portion, 6, has been fed down until the shell, 12, abuts the cylinder, 8, the forced rotation of the tip, 2, will turn the threaded plunger, 6, with the tip, causing the resilient walls of the shell, 12, to yield inwardly, and allowing the nodes or projections, 14, to ride out of the V-shaped channels and over the flat intervening side walls of the tube, 9, with a snapping or clicking action. This will notify the user that 30 the operation is not the normal feeding action, while at the same time preventing any real injury to the parts. The tip and barrel may be separated at any time by merely pulling them apart longitudinally, thus allowing 35 inspection of the mechanism and permitting the threaded plunger, 6, to be operated by hand while disassembled from the barrel for withdrawing it from the threaded part, 7, and either removing the clogged lead or inserting a new lead, as the case may require.

In Figures 6 and 7 I have illustrated a modification of this structure which is entirely suitable and satisfactory in a pencil which is adapted only to feed the lead outwardly from the tip terminal, 4, and not to withdraw or "repel" it. In this case the cylindrical shell, 12^a is fitted snugly in a cylindrical liner tube, 9^a, and while the shell may have slits, 13^a, to render it slightly resilient, there is no necessity for the nodes, 14,

and there is not even a semi-positive engagement between the shell, 12^a, and the bore of the barrel. The frictional engagement between these parts which are both cylindrical in this form of the device, is sufficient to hold the threaded plunger against rotation when the tip, 2, is rotated, but this friction is not sufficient to interfere with the longitudinal movement of the plunger in the barrel. With a right-handed thread the feeding action and the frictional drag of the shell, 12^a, in the liner tube, 9^a, tend to pull the tip, 2, against the end of the barrel, 1. But if this pencil were also provided with a coupling sleeve, 11, for withdrawing the lead, it will be seen that opposite rotation of the tip, 2, would tend to feed the tip away from the barrel, 1, by reason of the friction between the shell, 12^a, and the bore which would oppose upward or inward movement of the plunger in the bore. The parts could be readily pushed together, but the average user would not understand the situation and the tendency of the tip and barrel to separate during the "repelling" operation would appear as a defect. Therefore, this modified form is not recommended in combination with a coupling sleeve or other means for causing the lead to be withdrawn, as well as propelled outwardly in the tip. In the structure shown in Figures 1 to 5 the 95 projections, 14, on the shell, 12, do not frictionally engage the hexagonal guide tube, 9, but permit free sliding movement of the plunger along its axis within this bore.

Where barrels of moulded material, such as bakelite, are used, the tube, 9, may be dispensed with and the hexagon form moulded directly in the barrel.

I claim:

1. In a mechanical pencil, a threaded lead-propelling plunger, a barrel in which it is longitudinally movable, a hollow threaded member engaging the thread of the plunger, said hollow member being rotatable with respect to the barrel for moving the plunger, and means by which the plunger is yieldingly held against rotation in the barrel.

2. In a mechanical pencil, a lead-propelling plunger, means having a threaded portion, a barrel in which said plunger means is longitudinally movable, a hollow threaded member engaging the thread of the plunger means, said hollow member being rotatable with respect to the barrel for moving the plunger means, and yielding means operatively connecting the plunger means and barrel to normally prevent relative rotation thereof.

3. In a mechanical pencil, a threaded lead-propelling plunger, a barrel in which it is longitudinally movable, a hollow threaded member engaging the thread of the plunger, said hollow member being rotatable with respect to the barrel for moving the plunger, and a substantially cylindrical shell carried

- by the plunger and engaging the bore of the barrel, the wall of said shell being slit to make it radially resilient.
4. In a mechanical pencil, a threaded lead-propelling plunger, a barrel in which it is longitudinally movable, a hollow threaded member engaging the thread of the plunger, said hollow member being rotatable with respect to the barrel for moving the plunger, and a substantially cylindrical element carried by the plunger and in frictional engagement with the bore of the barrel.
5. In a mechanical pencil, a threaded lead-propelling plunger, a barrel in which it is longitudinally movable, a hollow threaded member engaging the thread of the plunger, said hollow member being rotatable with respect to the barrel for moving the plunger, and a member on the threaded member frictionally engaging the bore of the barrel and adapted to slip therein in the event of forced rotation of the threaded plunger in the barrel.
6. In a mechanical pencil, a threaded lead-propelling plunger, a barrel in which it is longitudinally movable, a hollow threaded member engaging the thread of the plunger, said hollow member being rotatable with respect to the barrel for moving the plunger, said barrel being provided internally with a V-shaped channel, means projecting from said plunger normally located in said channel and yieldable to permit it to ride out of the channel upon forced rotation of the plunger in its barrel.
7. In a mechanical pencil, a threaded lead-propelling plunger, a barrel in which it is longitudinally movable, a hollow threaded member engaging the thread of the plunger, said hollow member being rotatable with respect to the barrel for moving the plunger, said barrel being provided with a longitudinal V-shaped channel, and a substantially cylindrical shell on the threaded plunger having its cylindrical wall slit to make it radially resilient, and being provided with a convex projection normally located in said channel, but adapted to yield inwardly by reason of the resilience of the cylinder for disengagement upon forced rotation of the plunger in the barrel.
8. In a mechanical pencil, a threaded lead-propelling plunger, a barrel in which it is longitudinally movable, a hollow threaded member engaging the thread of the plunger, said hollow member being rotatable with respect to the barrel for moving the plunger, said barrel being provided with a polygonal bore forming V-shaped channels, and a cylindrical element carried by said plunger, and having inwardly yieldable walls normally tangent to the polygonal bore and provided with projections normally located within said channels to hold same against rotation
- in the bore except upon the application of unusual force.
9. In a mechanical pencil, a barrel having an axial opening, a tip mounted for rotation on the barrel, a tube carried by the tip extending into the axial opening of the barrel, a plunger assembly having a threaded connection with the tube and comprising a tubular component in contact with the axial opening and movable over the tube.
10. In a mechanical pencil, a barrel provided with an axial opening having a non-circular portion, a tip mounted for rotation on the barrel, a tube carried by the tip, a plunger assembly having a threaded connection with the tube and comprising a plunger rod extending into the tube and a tubular component adapted to operatively engage the non-circular portion of the axial opening and move over the tube.
11. In a mechanical pencil, a lead-propelling plunger means having a threaded portion, a barrel in which said plunger means is longitudinally movable, a hollow tubular threaded member engaging the threaded portion of the plunger means, said tubular threaded member being rotatable relative to the barrel for moving the plunger means, said plunger means and barrel being so formed as to resist relative rotation during normal longitudinal feeding movement of the plunger means and to permit relative rotation upon forced rotation of the plunger in the barrel.
